CLAIM

The ornamental design for dispenser for solid material, as shown and described.

DESCRIPTION

FIG. 1 is a top perspective view of a dispenser for solid material showing our new design;

FIG. 2 is a top plan view thereof;

FIG. 3 is a side elevational view thereof, the opposite side being a mirror image of the side shown;

FIG. 4 is a side elevational view taken ninety degrees from the side shown in FIG. 3, the opposite side being the same as the side shown;

FIG. 5 is a bottom plan view thereof; and

FIG. 6 is a top perspective view thereof showing the dispenser in a partially open position.

FIG.1

FIG.4

FIG.2

FIG.5
